RING FORMING AND APPLYING MACHINE

Charles F. Jackson, Jackson, Mich., assignor to Falls Spring & Wire Company, Detroit, Mich., a corporation of Michigan, and Great Lakes Spring Corporation, Chicago, Ill., a corporation of Illinois

Application September 24, 1948, Serial No. 50,930

5 Claims. (Cl. 1-2)

1

This invention relates to clip ring forming and applying mechanism and particularly to an improved mechanism of this character for forming and applying clip rings to spring supported upholstery and the like.

An important object of this invention is to provide a machine of this character in which the parts thereof are so organized and related to one another that immediately upon the formation of a clip blank it is delivered into the jaws for closing the clip blank upon work. Another important object of the invention is to provide a mechanism of this character in which the parts thereof are so formed that they may be inexpensively manufactured and assembled together and are so rugged and durable in construction that they may be operated rapidly and for long periods of use. A further important object of the invention is to provide a mechanism of this character in which the parts are separately operatively connected to a single power shaft which enables the parts to be readily adjusted with respect to one another to vary the time sequence of their respective operations and to be readily replaced by similar parts of modified construction without requiring the entire mechanism to be dismantled.

Important features of the invention relate to the provision for guiding the clip forming jaws and for varying the movement thereof to close the clip on work, to the provision for separately driving the moving parts from rotary cams carried by the power shaft, to the provision for feeding wire into position to be cut and formed into clip ring blanks, and to the provision for mechanically reciprocating the ring blank feeding member in both directions through a yielding connection which safeguards the feed member and associated parts from damage in the event the mechanism should be obstructed or clogged in operation.

Various other objects, advantages and meritorious features of the invention will become more apparent from the following specification, appended claims and accompanying drawings wherein:

Fig. 1 is a side elevation of a mechanism constructed in accordance with this invention partly broken away in section to show the interior relationship of the parts.

Fig. 2 is a front end view of the mechanism of Fig. 1, partly in section, taken along line 2-2 thereof.

Fig. 3 is a vertical sectional view through the mechanism of Fig. 1 taken along line 3-3 thereof,

2

Fig. 4 is a bottom view of the clip forming and applying portion of the mechanism taken along line 4-4 of Fig. 1.

Fig. 5 is a vertical sectional view taken along line 5-5 of Fig. 2 through the housing of the wire feeding mechanism.

Fig. 6 is a sectional view through the resilient driving connection for the clip feed bar, and

Fig. 7 is a diagram illustrating the relative relation of the cams for operating the moving parts of the mechanism.

In the illustrated embodiment of the invention there is provided a horizontal main supporting member or plate 10 above which is journaled for rotation a power shaft 12 extending longitudinally and in a fore and aft direction relative to the machine as a whole. The shaft 12 is supported in raised position above the plate 10 at its forward end by a bearing 14 and adjacent

its rear end by a similar bearing 16. Means for driving the shaft 12 is shown at the right of Fig. 1 in the form of a double pulley or sheave wheel 18 about which is trained a pair of endless drive belts 20-20 leading to a source of power not shown.

Depending from the plate 10 are the parts of the apparatus for feeding the wire, forming the wire into a clip ring blank, and closing the clip ring blank upon work. These parts are enclosed in a vertical housing consisting of a pair

30 of side supporting members 22-22 which are closed on their front side by two superimposed removable plates 24 and 26 and similarly closed on their back side by two superimposed removable plates 28 and 30. The two supporting side members are bridged by a vertically extending central web member 32 which may be integrally connected to the side members and which serve to divide the housing into a front chamber and a rear chamber in which certain portions of the mechanism are reciprocably mounted. The lower opened end of the housing is traversed by a horizontal extending member or arbor 34 which extends in a fore and aft direction in equal spaced relation to the side members 22-22. The rear end of the arbor is integrally connected to a supporting cross member 36 which, as shown in dotted outline in Fig. 4, is connected by bolts 38 or otherwise secured at its opposite ends to the back

35 faces of the side members 22-22. The lower end of the central web 32 terminates short of the side members 22-22 and in slight spaced relation above the arbor as shown in Fig. 1 to provide clearance for the movement of a clip ring blank along the arbor thereunder.

40 45 50 55

A continuous length of wire 40 is intermittently fed through the wire guide 42 in one of the side members 22 and transversely across the upper surfaces of the arbor. The latter, as shown in Figs. 2 and 3, is shaped to form a cut section of the wire into a clip ring blank thereabout, the upper portion of the arbor being wider than the lower portion and provided with rounded side edges for this purpose.

Reciprocably mounted and guided in each vertical chamber of the housing is a flat plate member of rectangular cross section. One such member is indicated at 44 and the other at 46. The former is located in the rear chamber of the housing and is connected at its lower end to a pair of clip ring blank forming jaws 48-48. The other plate member is located in the forward chamber of the housing and is connected at its lower end to a pair of clip ring blank closing jaws 50-50.

The clip forming jaws 48-48 are connected at their upper ends by links 52-52 to the lower end of the reciprocating member 44. As shown in Fig. 3, the links 52-52 are pivoted at their upper ends to a reduced end section of the member 44 and diverge away from one another for separate pivotal connection at their lower ends to the upper extremities of the jaws 48-48. Intermediate the length of the jaws, and on opposite sides thereof as shown in Fig. 1, there are provided two rectangular shaped plate members 54-54 which overlap the two jaws and are pivotally connected thereto. The pivotal mounting formed by the plates 54-54 is such that when the upper ends of the jaws are spread apart the lower ends collapse toward one another. Between the plates 54-54 and the upper end of the jaws there is provided a spring 56 which is seated in corresponding recesses in the jaws and acts to yieldingly urge the upper ends of the jaws apart. The jaws 48-48 are mounted in the housing for reciprocating movement and as they are thrust downwardly the lower ends thereof are shaped to cut off a section of wire 40 overlying the arbor and bend the wire section into a clip ring blank 58 partially encircling the upper portion of the arbor.

To cause the lower ends of the jaws 48-48 to contract upon one another and form a clip blank, the inside faces of the side members 22-22 of the housing are cut away as at 60-60 to provide opposed recesses into which the upper ends of the jaws may swing in the manner shown in full line in Fig. 3. The full line position in Fig. 3 illustrates the position assumed by the jaws at the lower end of their stroke. The dotted position of the plate member 44 indicates the height to which the member and the jaws are raised at the upper end of their stroke. In the latter position the inner walls of the side members 22-22 contract the upper ends of the jaws so that the lower ends thereof are spaced at a wider distance apart than the upper portion of the arbor in order that they may be received thereover as they approach the limit of their downward stroke. As the jaws 48-48 approach the lower limit of their travel the upper ends thereof are brought opposite the recesses 60-60 and swing outwardly thereinto by the links as the member 44 reaches the lower end of its stroke.

The jaw 48 adjacent to the wire guide 42 is shaped to cut off the wire section projecting beyond the guide member. As shown in Fig. 4, the guide member and the jaw are provided with slanting cooperating faces 62 and 64 respectively

for this purpose. The cooperating faces 62 and 64 slide past one another when cutting off a wire section and then separate from one another to the position shown in Fig. 4 when the lower ends of the jaws contract upon the arbor to form the clip ring blank 58. Moreover, to assist in the engagement of the jaws with the wire section overlying the arbor, the bottom of the jaws 48-48 are grooved as at 66 in Figs. 3 and 4 to engage the wire section and hold the same in engagement with the jaws following the severance thereof from the balance of the wire.

The clip closing jaws 50-50 are pivotally connected to their reciprocating member 46 in the manner shown in Figs. 1 and 2. The lower end of the plate member 46 is reduced in thickness to form a relatively thin plate extension 68 which, as shown in Fig. 1, is received between the upwardly opening slots in the upper ends of the jaws 50-50. A pivot pin 70 pivotally connects the upper end of each jaw 50 to the plate extension 68. The lower ends of the jaws 50-50 are yieldingly urged apart by a coiled spring 72 located intermediate the ends of the jaws and seated in corresponding recesses 74-74 in the jaws. The side walls 22-22 limit the outward spread of the jaws 50-50 throughout their extent of reciprocating movement. As shown in Fig. 1 the forward end of the arbor 34 terminates immediately adjacent to the vertical path of movement of the jaws 50-50. In their fully raised position the lower ends of the jaws 50-50 are disposed immediately opposite to the forward end of the arbor in position to receive a clip ring blank therefrom. Following reception of the clip blank, the jaws move downwardly and are caused to contract upon one another to close the clip blank upon work brought under the housing.

As the clip closing jaws 50-50 approach the lower end of their stroke they are urged toward one another by the provision of wedging elements projecting into the path of their movement. This provision comprises two inwardly projecting members 76-76 of corresponding shape and formation, each located in a side wall member 22-22 of the vertical housing and close to the lower end thereof. The inner projecting end of each member 76 is chamfered or beveled as at 78. The outer edge of each jaw 50 is provided with an angular face 80 which is adapted to slidably engage the inclined face 78 of the adjacent projecting member 76 and to be wedged by the latter to move the jaw inwardly as it reaches the lower end of its stroke. Both members 76-76 and their respective inclined faces 78 are disposed on the same level and function to contract both of the jaws toward one another at the same time and as they approach the lower end of their stroke to thereby close the clip between the jaws on work brought under the mechanism.

Each inwardly projecting jaw engaging member 76-76 is resiliently mounted in the housing and is capable of retracting outwardly to soften the impact of the jaws 50-50 thereon. As shown in Fig. 2, a cap member 84 is associated with each member 76 and is secured to the outer face of the side member 22 in which the former is located. Seated in the cap is a coiled spring 82, the inner end of which bears against the outer end of the jaw engaging member 76 and yieldingly urges the same inwardly. The outwardly yieldable movement of the member 76-76 thus provided allows the jaws to accommodate themselves to the object about which they are applying the clip ring blank. If the latter should be

relatively large and unyielding it will prevent complete closing of the ring thereon. In such an event, the members 76—76 will yield slightly outwardly with respect to the jaws as the latter approach their clip applying position and permit the completion of the stroke of the jaws and the operating member 46 regardless of whether or not the ring is completely closed on the object.

Slidably mounted on the arbor 34 is a clip ring blank feeding member in the form of a flat bar 86. This bar is mounted for reciprocating movement on the arbor from the full line position shown in Fig. 1 which is rearward of the plane of the clip forming jaws 48—48 to the forward position extremity of the arbor where it feeds the clip blank into the jaws 50—50. The bar 86 is slidably guided for reciprocating movement. For this purpose the rear end of the bar is connected to a cross member 88 which is slidably mounted on a pair of fixed guiding rods 90—90. The cross member is bored for slidably fitting the rods 90—90 and it is evident that slidable movement thereof on the rods will reciprocate the feeding bar backwardly and forwardly on the arbor.

The clip blank feeding bar 86 is reciprocated in opposite directions by drive means directly connected to the shaft 12. This includes a bell-crank lever 92 pivoted at 94 about a horizontal axis to a fixed bracket member 96 above the arbor. The lower end of the crank lever 92 is bifurcated and is received over a short cross pin 98 mounted in the member 88 and exposed for reception of the forked end of the lever. The opposite end of the crank lever 92 is pivotally connected to a link 100 which in turn is pivotally connected to the lower end of a reciprocating drive member 102. It is evident that upon reciprocating movement of the drive member 102 the link 100 and the crank arm 92 will function to drive the feeding bar 86 in a fore and aft direction on the arbor 34.

The wire 40 is supplied from a wire roll or other suitable source and advanced in intermittent movement through the guide 42 and over the arbor 34. The mechanism accomplishing this operation comprises a pair of peripherally grooved rollers 104 and 106 disposed in superimposed relationship on opposite sides of the wire, as best shown in Fig. 5. The upper roller 104 is journaled for rotation on a shaft in the form of a bolt member 108 which serves to clamp two plate members which together form a housing for a part of the intermittent drive mechanism. These members comprise a relatively thick member 110 and a flat relatively thin back member 112 secured together by the bolt 108 previously mentioned and additional bolts 114 to the thicker member. The larger member 110 is secured by long bolts 115 to the outer face of the side member 22 through which the wire is fed. It is recessed on the side thereof against which the plate 112 abuts and received therein is a gear wheel 116. The latter is pinned to a hub member 118 which is press fitted to shaft 120 for joint rotation therewith. The latter projects rearwardly from the back plate 112 and enters a circular housing 122 in which a one-way drive mechanism is located. The housing is reduced adjacent to its outer extremity to receive an arm 124 which, as shown in Fig. 3, is fixed thereto. The housing 122 is further reduced at its outer extremity and journaled for rotation in a forward extending section 126 of the fixed bracket 96 previously described.

The one-way drive mechanism is such that

when the arm 124 is rocked in a clockwise direction as in Fig. 3 it will drive the upper roller 104 in the direction to feed the wire 40 across the arbor. Its return, or counter-clockwise movement is not imparted to the roller member. The roller 106 is journaled for rotation about a shaft in the form of a bolt member 128 and is geared to the roller 104 for rotation therewith but in the opposite direction. As shown in Fig. 5, fixed to the roller 104 is a gear wheel 130 and similarly fixed to the roller 106 is gear wheel 132. The two gear wheels 130 and 132 are disposed in vertical alignment and mesh with one another so that when the roller 104 is rotated the roller 106 is likewise rotated but in the opposite direction to feed the wire toward the arbor.

The roller 106 is mounted on a rocking member which is capable of being adjusted to vary the compression with which the roller engages the wire. As shown in Figs. 3 and 4, the roller 106 and its associated gear 132 are mounted between the forked ends of a member 134 which is pivoted to a depending lug 136 on the plate 110 about a horizontal axis formed by the pin 138. The member 134 is of right angular formation as shown in Fig. 3 and the end section 140 thereof opposite to the forked end projects upwardly vertically alongside of the plate member 110. Threaded through the upwardly projecting section 140 is a screw member 142 carrying a knurled control knob 144 which when rotated in the direction to thread the screw member inwardly will cause the latter to abut the plate member 110 and rock the right angular member 134 about the pivot point 138 and increase the compression exerted by roller 106 on the wire member.

The various moving parts of the mechanism are driven from the power shaft 12 by separate cams jointly rotatable therewith. As shown in Fig. 1, the reciprocating plate member 44 of the clip forming jaws is provided at its upper end with rearwardly projecting roller 146 which rides in a recessed cam track 148 on the forward face of a circular member 150. Similarly the reciprocating plate member 46 of the clip closing jaws is provided with a roller 152 which rides in a recessed cam track 154 on the rear face of a circular member 156 mounted on the shaft 12. The upper end of the reciprocating member 102 for driving the feed bar 86 is similarly provided with a roller 158 which rides in a recessed cam track 160 of a circular member 162 on the drive shaft 12. Members 156 and 162 are each secured with a hub 164 and 166 respectively which are pinned to the shaft 12 for joint rotation therewith. The member 150 which drives the clip forming jaws is secured by bolts 168 to the front side of a cam member 170 which is pinned to the drive shaft 12.

Associated with the cam member 170 is an oscillating arm 172 which, as shown in Fig. 3, is pivoted on one side of the shaft 12 to a fixed support about a horizontal axis 174. The arm extends under the cam member 170 and carries a roller 176 which bears thereagainst and as the former rotates causes the roller and the arm 172 to oscillate in the vertical path about a pivot point 174. The opposite end of the arm 172 is disposed above the wire advancing rollers and pivotally connected thereto is a link 178 which extends downwardly for pivotal connection to the arm 124 of the one-way drive mechanism for the wire advancing rollers. The downward movement of the arm 172 is yieldingly resisted by a plunger 180 located immediately therebelow and yieldingly urged upwardly by a coiled spring 182.

The bottom end of the plunger is slidably mounted in a recess in the plate 10 and the lower end of the spring 182 is seated therein in the manner shown in Fig. 3 for urging the plunger upwardly into engagement with the arm 172 for holding the roller 176 in constant contact with the cam member 170.

The feed bar 86 for advancing the clip ring blanks along the arbor 34 is mechanically reciprocated directly from the drive shaft 12. In the event of blockage of the feed bar, which may be caused by an imperfectly formed clip blank or the presence of a foreign body, it is desired to provide novel means for slowing or stopping the advance of the feed bar without interrupting the operation of the remaining parts of the mechanism. For this purpose it is preferred to provide a resilient force transmitting member in the driving connection between the drive shaft and the feed bar. As shown in Figs. 1 and 6 such a resilient driving connection may be formed by dividing the link 100 into two telescoping sections, including the link member 100 previously referred to and a sleeve 184 which slidably fits the upper end of the link member. The sleeve is closed at its upper end as shown in Fig. 6 and is provided with an apertured ear 188 which is received between the lower forked extremity of the link member 102 and is pivotally connected thereto by a cross pin 188. Housed within the sleeve is a strong coiled compression spring 190 seated at its upper extremity against the closed end wall of the sleeve and at its lower extremity against the end of the link member 100. To prevent relative turning movement of the link member 100 and the sleeve and to limit the axial movement of one with respect to the other, the sleeve is provided with a longitudinal slot 192 through which projects a removable pin 194 carried by the link member.

In normal operation, the spring 190 is sufficiently strong to transmit the driving force of the link 102 to the bell crank lever 92 and the feed bar 86 without appreciable compression. However, in the event of blockage, either partial or complete, of the feed bar, the spring will yield allowing the feed bar to slow its advance or stop without interrupting the operation of the other moving parts of the apparatus. If such should occur the moving parts including the link 102 will repeat their operating strokes during which times the spring will compress instead of delivering the operating strokes to further advance the feed bar. In normal operation, the pin 194 is continuously in engagement with the lower end of the slot 192 and upon upwardly movement of the link 102 and the sleeve 184 the latter picks up the link member 100 rocking the bell crank lever in the direction to retract the feed bar.

Fig. 7 diagrammatically illustrates the operating cycles of the various cams and the relative positions of the moving parts with respect to one another. Figs. 1, 2 and 3 illustrate the position of the parts when the clip forming jaws 48-48 have completed the bending of a clip ring blank on the arbor. At this point in the operating cycle the clip closing jaws 50-50 are in an intermediate position of their stroke length and are moving upwardly. With reference to the cyclical diagram of Fig. 7 this position is represented by the letter A. As the parts continue their cycle of operation from this position, the clip closing jaws 50-50 continue to rise and approach the upper limit of their stroke when

the lower ends of the jaws will be disposed opposite to the outer end of the arbor 34 in position to receive a clip ring blank therefrom. As the jaws 50-50 approach the upper limit of their stroke, the clip forming jaws or dies 48-48 are moved upwardly and clear the clip formed thereby on the arbor. Immediately thereafter the feed bar 86 is urged forwardly on the arbor and commences to push the clip blank along the arbor toward the outer end thereof. The timing is such that as the clip closing jaws 50-50 reach the upper limit of their stroke, the feed bar pushes the clip blank into the jaws. During the downward movement of the jaws 50-50 with a clip ring therein, a section of wire 40 is fed transversely over the arbor preparatory to being cut and shaped by the clip forming jaws 48-48. After the jaws 50-50 have clinched the ring to work they commence to rise and during their rise the clip forming die members 48-48 move downwardly, cut off the section of wire overlying the arbor, and bend the wire section into at a time is formed and immediately thereafter a U-shaped clip blank on the arbor. One clip is advanced by the feed bar into the clip closing jaws 50-50.

What I claim is:

1. A clip ring forming and applying mechanism comprising, in combination, a horizontally extending arbor shaped to form a clip ring blank thereabout, means for feeding the end section of a wire transversely over the arbor, a pair of clip blank forming jaws pivotally swingable toward and away from one another, means for reciprocating said pair of clip forming jaws in a vertical path and causing the same to straddle the arbor at the lower end of its stroke and swing inwardly theretoward to form a clip ring blank on the arbor, one of said clip forming jaws being so shaped that in its downward movement it will cut off an end section of wire overlying the arbor, a pair of clip blank closing jaws pivotally swingable toward and away from one another, means for reciprocating said pair of clip closing jaws in a vertical path offset to the vertical path of movement of the clip forming jaws and from a position immediately opposite one end of the arbor to a clip applying position spaced therebelow, a clip blank feed member slidable longitudinally on the arbor, means for reciprocating said feed member a distance along the arbor between said paths of movement and for causing the feed member to advance a clip ring blank along the arbor to said end thereof and to retract same rearwardly of the position on the arbor where said pair of clip forming jaws cut off and form a clip blank thereon, and means for driving said reciprocating means for said pairs of clip forming and clip closing jaws and for driving said feed member in timed relation such that immediately following the formation of a clip blank on the arbor by the clip forming jaws it is advanced by the feed member to said end of the arbor and into the clip closing jaws at the time the latter reach the upper end of their stroke.

2. A clip ring forming and applying mechanism comprising, in combination, a horizontally extending rotating power shaft, a horizontally extending arbor disposed below said shaft in spaced parallel relation thereto and shaped to form a clip ring blank thereabout, means for feeding successive sections of wire transversely across the arbor, a pair of clip blank forming jaws, a pair of clip closing jaws, a pivotal mounting for each

of said pairs of jaws providing swinging movement of the jaws toward and away from one another, means operatively connecting the pivotal mounting for the clip blank forming jaws to said shaft for reciprocating the jaws in a vertical path between the shaft and the arbor, means operatively connecting the pivotal mounting for the clip closing jaws to said shaft for reciprocating the jaws in a vertical path offset to the vertical path of movement of the pair of clip blank forming jaws and between one end of the arbor and a clip applying position therebelow, means for guiding said pairs of jaws in their reciprocating movement and for causing each pair of jaws at the lower end of its stroke to swing toward one another, said last means causing the clip blank forming jaws to straddle the arbor at the lower end of their stroke and swing inwardly theretoward to form a clip ring blank on the arbor and further causing the clip closing jaws to swing toward one another at the lower end of their stroke to contract a clip ring blank received therebetween on work, a clip blank feed bar slideable longitudinally on the upper surface of the arbor between the vertical paths of movement of the two pairs of jaws, and means operatively connecting the feed bar to said shaft and operable to reciprocate the same the distance between said paths of movement, said operating connecting means for said pairs of jaws and for said feed bar causing reciprocation thereof during one complete revolution of the shaft and timing the clip blank feeding movement of the bar during the upward strokes of both pairs of jaws.

3. In a clip forming and applying mechanism, a pair of jaw members swingably mounted for movement toward and away from each other, means mounting said jaw members for joint reciprocating movement, means for feeding a clip ring blank into the jaws at one end of their stroke, and means for closing the clip ring blank received in the jaws on work at the other end of their stroke, said last means including a pair of wedging elements, one for each jaw member, projecting into the path of travel of the jaw members and cooperating with inclined faces thereon for wedging the jaw members together, and means yieldingly urging each of said wedging elements in the direction toward said jaw members.

4. In a clip forming and applying mechanism, a pair of jaw members disposed in side by side relationship and correspondingly shaped at one of their ends for receiving a clip ring blank and for closing the same on work, means providing a guide-way in which said pair of jaw members are reciprocatingly mounted, means for reciprocating said jaw members in said guide-way and for projecting the jaw members therefrom when applying a clip ring blank to work, a wedging element for each jaw member disposed in each opposite side wall of the guide-way and projecting into the path of travel of the jaw member, said wedg-

ing elements each provided with a face inclined to the path of travel of the jaw member with which it is associated and adapted to engage an inclined face on the jaw member to urge the same inwardly toward the other jaw member, resilient means yieldingly urging each of said wedging elements inwardly toward the path of travel of the jaw members, and means for adjusting the force of said resilient means on the wedging elements.

5. In a clip ring forming and applying mechanism, a horizontally extending arbor shaped to form a clip ring blank thereabout, means for feeding successive sections of wire transversely across the arbor, a pair of clip ring blank forming jaws, a pair of clip ring closing jaws, a separate pivotal mounting for each of said pairs of jaws providing swinging movement of each pair of jaws toward and away from one another, means for bodily reciprocating the pivotal mounting for the clip ring blank forming jaws to cause the jaws to move in a vertical path above the arbor and spaced from one end thereof, means for severing wire sections extending across the arbor in timed relation to the reciprocation of the clip blank forming jaws and for causing the latter to bend the severed wire sections on the arbor into clip ring blanks, means for bodily reciprocating the pivotal mounting for the clip ring closing jaws to cause the jaws to move in a vertical path offset to the vertical path of movement of the clip ring blank forming jaws and between said end of the arbor and a clip applying position therebelow, a clip ring blank feed member slideable longitudinally on the arbor, means for reciprocating said feed member the distance along the arbor separating the paths of movement of said pairs of jaws and for causing the feed member to move said end of the arbor to advance a clip ring blank along the arbor and into said clip ring closing jaws and for causing the feed member to return to the path of movement of the clip blank forming jaws, power means for driving each of said reciprocating means and correlating the operation thereof such that the feed member is reciprocated said distance once for every time said pairs of jaws are reciprocated, and a resilient force transmitting member in said feed member reciprocating means operable to permit a shortened feeding stroke of the feed member without interrupting the operation of the remaining parts of the mechanism.

CHARLES F. JACKSON.
